UNITED STATES PATENT OFFICE.

JOHN H. STONE, OF MOBILE, ALABAMA.

STRETCHER.

1,068,016.

Specification of Letters Patent. Patented July 22, 1913.

Application filed October 9, 1911. Serial No. 653,645.

To all whom it may concern:

Be it known that I, JOHN H. STONE, of Mobile, in the county of Mobile and State of Alabama, gentleman, having invented 5 certain new and useful Improvements in Stretchers, do hereby declare the following is a full, clear, and exact description of the same.

My invention relates to improvements in 10 stretchers, and has for its leading object the provision of an improved form of folding stretcher particularly adapted for the use of soldiers when in the field.

The further object of my invention is the 15 provision of a sectional folding stretcher which may be divided and parts carried by different persons to minimize the weight of pack carried by any individual.

Another object of my invention is the 20 provision of an improved stretcher provided with means whereby one end may be held higher than the other to both facilitate raising of the stretcher from the ground and also render the person resting on the 25 stretcher more comfortable by having the head elevated.

Other objects and advantages of my improved stretcher will be readily apparent by 30 reference to the following description taken in connection with the accompanying drawings, and it will be understood that I may make any modifications in the specific structure shown and described within the scope of my claims without departing from or exceeding the spirit of my invention.

Figure 1 represents a plan view of my complete stretcher in assembled condition. Fig. 2 represents a side elevation thereof. Fig. 3 represents a perspective view of one 40 of the sections in folded condition. Fig. 4 represents a similar view of the other section, and Fig. 5 represents a sectional view on the line 5—5 of Fig. 1.

In the drawings, the numeral 1 designates the iron tubes forming one section of my improved stretcher while the numeral 2 designates the tubes forming the other section thereof, each of the tubes 1 and 2 being formed at one end with a handle 3 and at the other end with a depending portion or leg 4 having a flat end 5 adapted to fit against the end 5 of the other section at that side of the stretcher.

The tubes 1 are connected by the fabric 55 6 while the tubes 2 are connected by the fabric 7, said fabrics extending from the

handles of the tubes almost to the leg portions 4 and being either of canvas or an asbestos cloth which will be indestructible by fire. When the stretcher is assembled I 60 preferably connect the inner edges of the strips 6 and 7 by the laces 8 passed through the eyelets 9 at the ends or edges of the strips.

To enable the two halves of my stretcher 65 to be instantly and firmly secured together I form in the ends of the portion 4 of the rods or tubes 2 the sockets 10 tapering downwardly and adapted to receive the lugs or projections 11 carried by the ends of the 70 tubes 1, said lugs wedging downward into the sockets 10 and securely locking the tubes 1 and 2 together.

In the use of my stretcher when the same is resting on the ground the legs 4 will together 75 form pivotal supports for the stretcher and by disposing an excess of weight at either end of the stretcher said end will be caused to rest on the ground and consequently the other end of the stretcher will 80 be raised to cause the device to assume an incline which will render the occupant more comfortable than is the case with the ordinary stretcher which rests flat on the ground. This position of the stretcher also renders 85 raising of the same easier, in that the handles at one end are in position where they may be readily grasped when depression of said handles will rock the stretcher on the legs to raise the other handles instead of 90 necessitating working of the fingers under the stretcher as is ordinarily necessary.

From the foregoing description taken in connection with the accompanying drawings the construction and use of my improved 95 stretcher will be readily apparent and it will be seen that I have provided a satisfactory stretcher which is light, durable and easy to carry and while occupying normally but small space when assembled will accommodate any ordinary person and which will command itself both on account of the ease with which it may be carried and also on account of the position in which the supporting legs holds the same and facilitates 100 lifting thereof.

I claim:

1. A stretcher, comprising a pair of tubes each of which terminates in a downturned socketed end, a second pair of tubes each of 110 which terminates in a downturned end, having a projecting lug for engagement in

the socket of the end of one of the first tubes and fabric strips connecting the tubes of each pair.

2. A stretcher comprising pairs of parallel tubes, each pair being connected by a fabric, one end of each of the tubes having a depending member, the depending members of one pair of tubes being provided with means for detachable engagement with the depending members of the other pair

of tubes, the engaged depending members forming feet for elevating the stretcher, a short distance to permit the convenient grasping of the handles.

In testimony whereof I affix my signature, in the presence of two witnesses.

JOHN H. STONE.

Witnesses:

F. E. REITES,
L. E. OWEN.
